CLAIM

The ornamental design for a locking device for bag appurtenance, as shown and described.

DESCRIPTION

FIG. 1 is a front, top, and right sides perspective view of a locking device for bag appurtenance, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line 8-8 shown in FIG. 2.

The long dash short dash broken lines and arrows shown in FIG. 2 are used to identify the cross-sectional view and form no part of the claimed design.

1 Claim, 3 Drawing Sheets
